UNITED STATES PATENT OFFICE.

GEORGE R. WARD, OF NEW YORK, N. Y., ASSIGNOR, BY MESNE ASSIGNMENTS, TO LUCIUS G. FISHER, OF NEW YORK, N. Y.

PULP-MOLDING MACHINE.

SPECIFICATION forming part of Letters Patent No. 794,903, dated July 18, 1905.

Application filed July 26, 1901. Serial No. 69,770.

To all whom it may concern:

Be it known that I, GEORGE R. WARD, a citizen of the United States, residing at New York, State of New York, have invented certain new and useful Improvements in Pulp-Molding Machines, of which the following is a clear, full, and exact description.

My invention relates to a machine for forming articles from a suitable pulp, preferably wood-pulp; and my object is to provide a machine which shall be simple, accurate, and speedy in its action.

My invention will be defined in the claims.

In the drawings showing the preferred embodiment of my invention, Figure 1 is a side elevation. Fig. 2 is a plan view, and Fig. 3 a central vertical section of Fig. 1.

In carrying out my invention I have provided a rotating carrier which preferably rotates on a horizontal axis, the carrier having thereon, preferably, a succession of perforated mold-faces, the general plane of a mold-face being substantially perpendicular to the plane in which said carrier rotates. I have also provided a means for depositing pulp on such mold-face, preferably by causing it to dip into a vat of pulp and applying suction through said face when immersed. In order to compress the layer of pulp deposited on the mold-face, I prefer to use a second mold-face adapted to reciprocate toward and away from the first face and suitable actuating means adapted to press said second face against said first face in a direction toward the axis of the carrier. In the embodiment of my invention shown in the drawings the mold-faces are situated in pairs, one face of each pair being fixed to the carrier and the other face, which co-operates therewith, reciprocating toward and away from it and also traveling with the carrier. Thus each pair of faces forms a mold which travels.

In the embodiment of my invention shown in the drawings, 1 is the mold-face carrier, which rotates on a horizontal axis, in this case being mounted upon a horizontal shaft 2, supported in suitable bearings, as shown, and turned by a gear-wheel 12. As the axis of rotation is horizontal, the plane of rotation

of the carrier is vertical. The carrier and 50 shaft may be hollow, as shown, if desired. 4' is a diaphragm forming a division through the carrier. On the carrier is located a perforated mold-face 3, whose general plane is perpendicular to the plane of rotation of the 55 carrier. I prefer to provide a succession of mold-faces on the carrier and have shown another similar one, 4, thereon, the two said faces forming a succession of faces. These faces are preferably convex. In order to deposit a layer of pulp on each of said faces, I prefer to provide a suitable vat 6, containing pulp, as shown, of a height so that said faces will dip into and rise from the same in succession. As part of the means for depositing 60 the pulp on the face 4 I have in the drawings provided a hollow tube 10, communicating with the hollow part of the carrier, over which face 4 is located, within which suction and compression may be exerted by any suitable means, as indicated by the arrows. Illustration of such a device is not necessary to those skilled in the art in order to understand my invention. As the face 4 rotates downward and passes into the pulp suction may be 65 applied, as shown by the right-hand arrow-head, and cause a layer of pulp to be deposited thereon. In order to firmly compress the layer of pulp upon the face sufficiently to squeeze out water from the pulp and partially 70 or completely form the article, I have provided a second mold-face, which is adapted to move toward and away from said face 4, and suitable means for positively pressing the former face against the layer of pulp on 75 face 4. This movable face 4^a is in the embodiment of my invention shown in the drawings supported on the carrier by means of slide-rods 5 thereon. As the carrier rotates in the direction of the arrow in Fig. 1 face 4^a 80 will strike against cam 7, which will cause said face 4^a to move and will press it firmly against face 4, compressing the pulp on said face and forming the article. It will be observed that the cam 7 exerts a pressure in a 85 direction substantially perpendicular to the axis of the carrier—in this case toward or transversely of said axis. This is of advan-

tage, for when the carrier is mounted on a rotating shaft perpendicular to the plane of rotation of the carrier the pressure is exerted on it, which is a mechanical advantage.

5 In the embodiment of my invention shown in the drawings this pressure is exerted while both faces 4 and 4^a are traveling and in contact with the layer of pulp, and I prefer to do this in some cases, as the rotation then 10 does not have to be stopped. It will be observed that the face 4^a and the cam 7 together constitute a reciprocating means for compressing the layer of pulp. The carrier and cam also constitute an actuating device or 15 actuator for carrying face 4 into the pulp and then relatively against face 4^a, although in this case face 4^a moves toward face 4. A hollow pipe connects mold-face 4^a with hollow shaft 2, by which suction and compression 20 may be applied to face 4^a, as indicated by the arrows. Another mold-face 3^a, similar to face 4^a, may also be provided and attached to the slides 5, so that when one mold closes the other one opens, as shown, and 25 face 3^a may also have a pipe 8 connecting with the left side of shaft 2, by which suction and compression may be applied to it, as indicated by the arrows. A pipe 11 connects with mold-face 3, and suction and 30 compression are indicated by arrows. When a mold opens, air may be forced into the carrier and through a face (such as 3) to loosen the article, if desired. It is not material to my invention how the article is removed 35 from the mold-face.

I am aware that many variations from the constructions heretofore described may be made without departing from the spirit of my invention, and I therefore do not limit myself to the embodiment herein disclosed.

What I claim is—

1. In a machine for forming articles from pulp in combination, a plurality of traveling molds, each of the same being composed of 45 mold-faces adapted to form an article between them, one of the faces of each mold being movable toward and away from the other face, means to supply suitable pulp to said molds, means to press the faces of said molds together to form the article, and a connection between a movable face in each mold to open one mold as the other mold closes.

2. In a machine for forming articles from pulp in combination, a shaft, a rotating carrier thereon bearing a plurality of mold-faces adapted to form an article between them, means to supply suitable pulp to said mold, and means to apply pressure toward said shaft to one of said faces to press said faces together 60 and form said article.

3. In a machine for forming articles from pulp in combination, a shaft, a rotating carrier thereon bearing a plurality of mold-faces adapted to form an article between them, 65 means to supply suitable pulp to said mold,

and means to apply pressure toward said shaft to one of said faces to press said faces together at a point farther on in the travel of said carrier to form said article.

4. In a machine for forming articles from 70 pulp in combination, a vertically-rotating carrier bearing a plurality of molds, each of said molds having a relatively stationary mold-face and a relatively movable face nesting therewith, said relatively movable faces being 75 connected together whereby one mold opens as the other closes, a pulp-vat into which said molds dip to receive a layer of pulp between the faces thereof, and means located farther on in the rotation of said molds to successively 80 press the faces of each mold together to form the article.

5. In a machine for forming articles from pulp in combination, a vertically-rotating carrier bearing a plurality of molds, each of said 85 molds having a relatively stationary mold-face and a relatively movable face nesting therewith, said relatively movable faces being connected together whereby one mold opens as the other closes, means to supply a layer of 90 pulp between the faces thereof, and means located farther on in the rotation of said molds to successively press the faces of each mold together to form the article.

6. In a machine for forming articles from 95 pulp in combination, a shaft, a carrier thereon bearing a plurality of molds, each of said molds being composed of a pair of perforated nesting mold-faces movable relatively toward each other, said movable faces being connected 100 whereby one mold opens as the other closes, a pulp-vat into which said molds dip to receive a layer of pulp, a cam to successively press said molds together, at a point farther on in the rotation of said carrier, to form said article.

7. In a machine for forming articles from pulp in combination, a rotating shaft, means to rotate the same, a mold carried on said shaft and having a plurality of nesting mold-faces connected with said shaft and including a perforated mold-face, and a connection between said perforated mold-face and said shaft whereby a draft of air may be passed through the same.

8. In a machine for forming articles from pulp in combination, a rotating shaft, means to rotate the same, a mold carried on said shaft and having a perforated mold-face, and a connection between said perforated mold-face and said shaft whereby a draft of air may be passed through the same in either direction.

9. In a machine for forming articles from pulp in combination, a rotating shaft, means to rotate the same, a mold carried on said shaft 125 and having a perforated mold-face, and a connection between said perforated mold-face and said shaft whereby a draft of air may be passed through the same to loosen said article located on said face.

10. In a machine for forming articles from pulp in combination, a rotating shaft, means to rotate the same, a mold carried on said shaft and having a perforated mold-face, and a connection between said perforated mold-face and said shaft whereby a draft of air may be forced through the same to loosen said article located on said face.
11. In a pulp-machine in combination, a rotating carrier having thereon a perforated mold-face, means to automatically deposit a layer of pulp thereon, and means to firmly compress said layer upon said face in a direction perpendicular to the axis of said carrier.
15. 12. In a pulp-machine in combination, a rotating carrier having thereon a perforated mold-face, means to automatically deposit a layer of pulp thereon, and means to firmly compress said layer upon said face in a direction toward the axis of said carrier.
20. 13. In a pulp-machine in combination, a rotating carrier having thereon a perforated mold-face, means to automatically deposit a layer of pulp thereon, and means to firmly compress said layer upon said face in a direction toward the axis of said carrier and comprising a second mold-face movable toward and away from said first face and means to force said second face against said first face.
25. 14. In a pulp-machine in combination, a rotating carrier having thereon a perforated mold-face substantially perpendicular to the plane of rotation of said carrier, means to automatically deposit a layer of pulp thereon, and means to firmly compress said layer upon said face in a direction perpendicular to the axis of said carrier and comprising a second mold-face adapted to move toward and away from said first face, and means to positively force said second face against said first face.
30. 15. In a pulp-machine in combination, a rotating carrier having thereon a perforated mold-face substantially perpendicular to the plane of rotation of said carrier, means to automatically deposit a layer of pulp thereon, and means to firmly compress said layer upon said face in a direction perpendicular to the axis of said carrier and comprising a second mold-face adapted to move toward and away from said first face, and means to positively force said second face against said first face.
35. 16. In a pulp-machine in combination, a vat, a carrier rotating on a substantially horizontal axis and having thereon a succession of perforated mold-faces substantially perpendicular to the plane of rotation of said carrier and dipping in succession into said vat, means to automatically deposit a layer of pulp upon said faces in succession, and means to firmly compress said layer upon said faces in succession and in a direction toward the axis of said carrier.
40. 17. In a pulp-machine in combination, a vat, a carrier rotating on a substantially horizontal axis and having thereon a succession of perforated mold-faces substantially perpendicular to the plane of rotation of said carrier and dipping in succession into said vat, means to automatically deposit a layer of pulp upon said faces in succession, and means to firmly compress said layer upon said faces in succession and in a direction toward the axis of said carrier.
45. 18. In a pulp-machine in combination, a rotating carrier having fixed thereon a perforated convex mold-face, means to automatically deposit a layer of pulp thereon, and means to automatically firmly compress said layer upon said face in a direction toward the axis of said carrier.
50. 19. In a pulp-machine in combination, a rotating carrier having fixed thereon a perforated convex mold-face, means to automatically deposit a layer of pulp thereon, and means to automatically firmly compress said layer upon said face in a direction toward the axis of said carrier and comprising a second mold-face adapted to move toward and away from said first face and means to positively force said second face against said first face.
55. 20. In a pulp-machine in combination, a rotating carrier having fixed thereon a succession of perforated convex mold-faces, means to automatically deposit a layer of pulp thereon in succession, and means to automatically firmly compress said layer upon said faces in succession and in a direction toward the axis of said carrier.
60. 21. In a pulp-machine in combination, a pulp-vat, a carrier rotating on a substantially horizontal axis and having fixed thereon a succession of perforated convex mold-faces dipping in succession into said vat, means whereby suction may be applied through said faces when in said vat to deposit a layer of pulp thereon, and means to automatically firmly compress said layer upon said faces in succession and in a direction toward the axis of said carrier.
65. 22. In a pulp-machine in combination, a vat, a carrier rotating on a substantially horizontal axis and having fixed thereon a succession of perforated mold-faces dipping in succession into said vat, means whereby suction may be applied through said faces while in said vat to deposit a layer of pulp on said faces in succession, and means to firmly compress said layer upon said faces in succession in a direction toward the axis of said carrier and while said faces are traveling.
70. 23. In a pulp-machine in combination, a rotating carrier having thereon one or more perforated mold-faces, means to automatically deposit a layer of pulp on said face, a second molding device adapted to coöperate with said face to mold the article between them, and means to compress the two together in a direction transverse to the axis of rotation of said carrier, said molding device being adapted to travel along with said other face during the

time when said molding device is in contact with said layer.

24. In a pulp-machine in combination, a rotating carrier having thereon one or more perforated mold-faces, means to automatically deposit a layer of pulp on said face, a reciprocating mold-face adapted to coöperate with said first face to mold the article between them, and means to positively compress the two together in a direction transverse to the axis of rotation of said carrier, said reciprocating mold-face being adapted to travel along with said other face during the time when said reciprocating mold-face is in contact with said layer.

25. In a pulp-machine in combination, a rotating carrier having thereon a perforated

mold-face substantially perpendicular to the plane of rotation of said carrier, means to automatically deposit a layer of pulp on said face, a second molding device adapted to co-operate with said face to mold the article between them, and means to compress the two together in a direction transverse to the axis of rotation of said carrier, said molding device being adapted to travel along with said other face during the time when said molding device is in contact with said layer.

Signed at New York, N. Y., this 23d day of July, 1901.

GEORGE R. WARD.
